Primary Examiner — George D Kirschbaum*Assistant Examiner* — Jennifer Watkins*(74) Attorney, Agent, or Firm* — Daniel W. Sullivan**CLAIM**

The ornamental design for a sock, as shown and described.

DESCRIPTION

FIG. 1 is a perspective view of a first embodiment of the sock of this invention;

FIG. 2 is a lateral side elevation view of a first embodiment of the sock of this invention;

FIG. 3 is a plan view of a sole portion of a first embodiment of the sock of this invention;

FIG. 4 is a plan view of a top portion of a first embodiment of the sock of this invention;

FIG. 5 is a medial side elevation view of a first embodiment of the sock of this invention;

FIG. 6 is a front elevation view of a first embodiment of the sock of this invention;

FIG. 7 is a rear elevation view of a first embodiment of the sock of this invention; and,

FIG. 8 is a perspective view of a second embodiment of the sock of this invention.

In FIGS. 1-8, the broken lines showing a portion of a human foot are for the purposes of illustrating environment which forms no part of the claim. The broken lines shown on the sock are for the purpose of illustrating portions of the sock which form no part of the claim. The set of symbolic bracketed wave lines located at the ankle of the sock in FIG. 8 show a symbolic break in the length of the sock. The appearance of any portion of the article between the break lines forms no part of the claimed design.
